BY Chas. W. Co.

UNITED STATES PATENT OFFICE

133,489

DESIGN FOR A RAKE

William Albert Wurster, Portsmouth, Ohio

Application June 17, 1942, Serial No. 107,223

Term of patent 14 years

To all whom it may concern:

Be it known that I, William Albert Wurster, a citizen of the United States, residing at Portsmouth, in the county of Scioto, and State of Ohio, have invented a new, original, and ornamental Design for a Rake, of which the following is a specification, reference being had to the accompanying drawing, forming part thereof.

In the drawing:

The figure is a perspective view of a rake, showing my new design.

I claim:

The ornmanetal design for a rake, as shown.

WILLIAM ALBERT WURSTER.
